Inventor;

Jonathan Faw.

UNITED STATES PATENT OFFICE.

JONATHAN FAW, OF LOCKLAND, OHIO.

IMPROVEMENT IN RAG-ENGINES OF PAPER-MAKING MACHINES.

Specification forming part of Letters Patent No. 38,735, dated June 2, 1863.

To all whom it may concern:

Be it known that I, JONATHAN FAW, of Lockland, Hamilton county, Ohio, have invented a new and improved mode of reversing the stock from the long to the short and from the short to the long circumference in engines used for grinding stock into pulp for the manufacture of paper while grinding the same; and I do hereby declare that the following is a full, clear, and exact description of the construction and operation of the same, reference being had to the accompanying drawings in this case, in which—

Figure 1 represents a plan or top view of an ordinary rag-engine cap, with the deflectors which constitute my invention attached thereto; Fig. 2, a longitudinal elevation, and Fig. 3, a transverse section, of the same. Fig. 4 represents a plan of my deflector, and Fig. 5 a side elevation of the same.

The nature of my invention consists in providing deflectors which are placed on the inside of the cap of a rag-engine, and which, in combination with the cap, deflect the stock in the engine during the process of grinding from the inside or short circumference to the outside or long circumference.

The object of my invention is to secure uniformity in the quality of the pulp.

The deflector E may be made either of wood or metal, with a plain surface or with a concave surface, and is represented with a concave surface in the drawings above referred to, and may be permanently attached to the inside of the ordinary cap of any rag-engine of the usual kind, immediately behind the roll of the engine, as shown at Fig. 6, and may be used at any stage of the grinding, whether the stock be coarse or fine, long or short. I propose to place a deflector on each side of the cap, as shown in the drawings by Figs. 1 and

3, either of equal height, as shown, or at different elevations.

The stock, in passing between the roll and the bed-knives, is thrown violently upward immediately behind the roll, and, thereby coming in contact with the deflectors, is thereby deflected from the long to the short and from the short to the long circumference of the engine during the process of grinding, thereby overcoming a difficulty at present existing in all rag-engines, by reason of which the stock on the inside or short circumference is ground much finer than that on the outside or long circumference. The shortest distance traveled by the stock is in passing around the mid-fellow, which is the support of the end of the roll in the center of the engine. The longest distance traveled by the stock is in passing around the engine next to the outside, which will be found to be equal to about twice the distance around the mid-fellow.

By placing deflectors constructed and arranged as above described in the cap of ordinary rag-engines the stock is constantly changing position, being diverted in its course from the center or mid-fellow to the circumference of the engine, and vice versa, during the process of grinding, in consequence of which a more even pulp is made, thus facilitating the operation of grinding and making a better quality of paper.

What I claim as my invention, and desire to secure by Letters Patent, is—

The combination, with the cap of a rag-engine, of the deflectors E, constructed and arranged as and for the purposes set forth.

JONATHAN FAW.
